UNITED STATES PATENT OFFICE.

JOSEPH H. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

HEEL-BUILDING MACHINE.

1,400,695.

Specification of Letters Patent. Patented Dec. 20, 1921.

Application filed May 16, 1918. Serial No. 235,000.

To all whom it may concern:

Be it known that I, JOSEPH H. POPE, a citizen of the United States, residing at Hamilton, in the county of Essex and State 5 of Massachusetts, have invented certain Improvements in Heel-Building Machines, of which the following description, in connection with the accompanying drawings, is a specification, like reference characters on 10 the drawings indicating like parts in the several figures.

This invention relates to heel building machines and has particular reference to means for controlling the alinement of the 15 lifts of a heel blank, the application of pressure to the blank while a heel building nail is being driven, and the provision of means for insuring the safety of the operative during the operation of the machine upon the 20 blank.

In machines of the general type to which this invention is applicable, a contractile 25 heel form is provided. While the form is expanded a series of lifts sufficient for a heel blank is piled into the form, which is then contracted to engage the lateral surface of the heel, aline the lifts properly and maintain them in alinement while the blank 30 is subjected to pressure and a nail driven through it to secure the lifts together. A typical example of this style of heel building machine is illustrated and described in Patent No. 1,056,720, granted March 18, 35 1913, Tripp.

In machines of the type referred to the mechanism for contracting the form jaws upon the lateral surface of the heel is operated by a foot treadle independently of the pressure and nailing mechanism, and it has been possible to apply pressure to the 40 pile of lifts and to drive one or more nails through them while the form jaws were open or out of engagement with the heel. 45 This often resulted in causing the lifts to slide one upon another with the consequent distortion of the heel and was particularly troublesome when building heels with one or more pieced lifts where the pieces were 50 likely to become separated. In the machine of the above-mentioned patent, also, the starting of the power mechanism is effected by drawing forward the arm carrying the presser foot and, the machine having been

started, it has been possible at times for the 55 arm to fall backward sufficiently before the presser foot engaged the heel so that one or more of the heel building nails would not engage and clench upon the presser foot. As a further incident of the operation of 60 these machines, it has been possible to cause the depression of the presser foot upon the heel before the operative had removed her fingers from the mold, with the consequent 65 possibility of personal injury.

The object of the present invention is to overcome the difficulties above outlined, and to this end a feature of the invention consists in the provision in a heel building machine having a contractile heel form and mechanism for performing an operation upon the heel, of automatic means for contracting the form upon the lateral surface of the heel, preferably yieldingly, prior to the application of the vertical pressure which forces the lifts into intimate contact with each other, in combination with separate means for opening, or expanding the form. This automatic means may conveniently take the form of a spring or equivalent yielding device operating to close the jaws of the heel form and controlled by a cam or other element of the power mechanism of the machine in such a way that the heel form is maintained in expanded or open condition while the lifts are being introduced into it and is automatically closed upon the heel to aline the lifts after the machine is started and prior to the engagement of the presser foot with the topmost lift. By reason of the yielding contraction of the form, it operates to aline the lifts with certainty and accuracy, regardless of variations in their sizes.

A further feature of the invention consists in the provision of means for preventing movement of the presser foot away from over the path of the heel building nail or nails after the machine is started and before the nail or nails have been driven and clenched. In a practical form of the invention this feature may be embodied in a latch constructed and arranged to permit the presser foot to be drawn forward into operative position over the heel and then to lock and retain it in that position until it has descended to exert pressure on the heel.

while the nails are driven, whereupon the presser foot is released and allowed to fall back to inoperative position.

A still further feature of the invention 5 consists in a safety device comprising a presser foot or platen laterally movable over and away from the receptacle containing the heel and so constructed and arranged that in its movement into operative position over the heel it will engage and push away the fingers of the operative in case they have not been removed in time, thus avoiding any danger of her fingers being caught and injured.

15 These and other features of the invention will best be appreciated and understood from the following detailed description of one embodiment thereof when read in connection with the accompanying drawings, in 20 which,

Figure 1 is a perspective view of the invention applied to a well-known form of heel building machine;

Fig. 2 is a side elevation partly in section of the mechanism shown in Fig. 1;

Fig. 3 is a view of a detail of the mechanism for locking the pressure foot arm in operative position; and

Fig. 4 is a sectional view of the safety 30 mechanism of the presser foot.

The invention will be described as embodied in a machine constructed like that shown in Patent No. 1,056,720, above referred to, and reference may be had to that 35 patent for a full disclosure of the details of construction of those features of a heel building machine which are not novel, *per se*, with the present inventor.

Referring now to the drawings, 40 indicates the frame and 12 the table of a heel building machine. Mounted upon the table 12 is a die and form holder 14 in suitably formed guiding grooves in which is secured a nailing die 16 having the usual driver 45 and nail guiding holes 18 and, upon the upper surface of which is supported a contractile heel receptacle or form comprising a breast member 20 and side jaws 22, 24. The jaws 22, 24 are carried by the ends of 50 arms 26, 28 pivoted respectively at 30, 32 to the member 14. The arm 26 is provided with an extension 33 and a spring 34 connected at one end to the arm 33 and at the other end to a stationary bracket 36 bolted 55 to the machine frame tends normally to swing the jaws which are interconnected by a pin and slot as shown in Patent No. 1,148,716, granted August 3, 1915, upon the application of J. H. Richardson, in a direction to close the jaws upon the lateral surface of the heel to aline the lifts preparatory to the driving of the heel building nail.

60 The outer end of the extension 33 is connected by an adjustable link 42 to a cam 65 lever 44 which moves about a stationary

pivot 46 and is actuated to expand or open the forming jaws in opposition to the spring 34 to facilitate the introduction of the lifts by a cam 48 mounted upon the main driving shaft 49 of the heel building machine.

70 A beam or arm 50 corresponding to the beam 122 of Patent No. 1,056,720, previously mentioned, carries a presser foot or platen 52 for engaging the upper face of the heel and pressing the lifts together. As in the 75 said patent, the act of swinging the presser foot over the heel in the form automatically releases the starting clutch and causes the presser foot to be lowered by power and the heel building nail or nails to be driven. The 80 mechanism for performing these operations is fully shown and described in the said patent and a detailed description thereof need not be repeated here.

85 Cam 48 is so disposed upon the shaft 49 that when the machine stops the cam is in engagement with the cam arm 44 and the form jaws 22, 24 are held open to permit the easy and rapid introduction of lifts into the form. When the requisite number of lifts 90 for a heel blank have been introduced into the form the arm 50 is drawn forward to bring the presser foot over the blank and to start the machine. Immediately upon the starting of the machine the cam 48 moves out of engagement with the arm 44, whereupon the spring 34 acts immediately to close the jaws 22, 24 upon the lateral faces of the heel alining the lifts and locating the blank accurately with relation to the nail driving mechanism. In the continued operation of the machine the presser foot 52 carried by the arm 50 descends to apply pressure to the blank and then the heel building nail or nails are driven, their points, if they 100 protrude through the upper surface of the blank, being clenched upon the pressure foot.

105 Heretofore, in machines of this type it has sometimes occurred that the operative 110 would draw the arm 50 forward quickly and immediately release it. If the arm were drawn forward somewhat violently it would sometimes rebound rearwardly and although the power mechanism of the machine was 115 started, the presser foot would have moved sufficiently rearwardly by the time it had engaged the heel so that one or more of the heel building nails would escape engagement with it and would not be properly clenched. 120 To overcome this possibility, I have provided mechanism which will now be described.

125 A pin 54 is slidably mounted in a boss 56 secured to, or forming part of, the frame of the machine. A spring 58 held under tension by screw 60, presses against the pin 54, holding it yieldingly inwardly with its end in the path of a slide 62, mounted for movement in a vertical groove 64 formed in the 130

arm 50. A spring 66 attached to the slide 62 and to a pin 68 inserted in the arm 50 tends to draw the slide 62 upwardly until the lower end of a slot 70 formed in the slide 5 engages a screw 72 which is likewise inserted in the arm 50. A beveled face 74 is formed upon the slide in proper position to engage the yielding pin 54 in the forward movement of the arm 50. The relation of 10 the parts, however, is such that when the arm 50 has reached the limit of its forward movement, the pin 54 snaps in behind the slide 62, thus holding or locking the arm 50 positively against falling backward and 15 maintaining the presser foot 52 in alignment with the nail drivers.

As the arm 50 descends during the operation of the machine a forwardly extending hook 76 upon the lower end of the slide 20 62 engages and passes by the hook upon the upper end of a dog 78 pivoted at 80 to the machine frame and yieldingly drawn rearwardly by a spring 82. Pin 84, which serves 25 as a means for connecting the spring 82 to the dog 78, also engages a surface 86 formed upon the frame of the machine which acts as a stop to limit the rearward movement of the dog. In the operation of the machine the arm 50 descends sufficiently to cause the 30 hook 76 to pass by the hook on the dog 78, which then snaps in over the hook 76, as shown in Fig. 3. As the arm 50 again rises, the dog 78 prevents the slide 62 from rising, holding it in such a position that its 35 upper surface may move backward beneath the end of the pin 54, as the arm 50 swings backward. By the time the arm has reached its position of rest, as shown in Fig. 1, the slide 62 has been released from the hook on 40 the dog 78, the rearward movement of which is limited by the pin 84 and the surface 86, and the upper end of the slide has passed from beneath the pin 54, permitting the spring 66 to restore the slide to its initial position 45 ready for the next operation. It will be apparent that no matter how suddenly or violently the arm 50 is drawn forward, it will be impossible for the presser foot 52 to move backwardly out of alignment with the 50 nail drivers until after the nails have been driven and the operation of the machine upon the heel blank has been completed.

Referring now to Fig. 4, the presser foot 52 has an upwardly projecting stem 90 arranged to slide vertically in a guiding hole formed in the lower end of the plunger 92, which is mounted in the head 94 at the upper end of the arm 50. A screw 96 is threaded into the plunger 92 and has a reduced end 55 portion 98 which projects into a slot 100 in the stem 90. A screw 102, threaded into the upper end of the stem 90 and maintained in adjusted position by a check nut 104, is arranged to engage the end 98 of the screw 60 65 96 and to limit adjustably the downward

movement of the presser foot relatively to the plunger 92. The spring 106 serves to maintain the screw 102 yieldingly in engagement with the element 98, while a sleeve 108 projecting upwardly from the presser 70 foot incloses the space between the presser foot and the lower end of the plunger 92, excluding dirt and preventing anything from becoming caught between the opposing surfaces. A slot 110 in the sleeve permits 75 the introduction of a screw driver to remove the screw 96 when it is desired, to dismount the presser foot from the plunger. The plunger is adjusted vertically by means of a hand wheel 112 to such a position that the 80 path of movement of the lower face of the presser foot is as indicated by the dotted line 114, in Fig. 2, that is to say, the presser foot in its forward movement will barely clear the jaws of the heel form and the upper surface of the heel blank. In the event that the operative has not removed her fingers from the form, the presser foot in its forward movement will push them away to a position of safety, there being insufficient 85 space for her fingers between the presser foot and the heel.

The adjustment of the screw 102 is such that the space between the lower end of the plunger 92 and the upper face of the presser 90 foot is so related to the downward movement of the arm 50 in applying pressure to the heel that the plunger will engage the presser foot and, through the presser foot, the requisite pressure will be applied to the 100 lifts to force them together and hold them firmly while the nail or nails are being driven. After the presser foot 52 has engaged the heel, the spring 106 yields during the downward movement of the plunger 105 92, permitting the pressure to be applied positively upon engagement of the plunger with the presser foot, and when the plunger again rises the spring acts to restore the parts to their initial "safety" position as 110 illustrated in Fig. 4.

While the particular embodiment of the invention selected for disclosure herein has been specifically described as included in the organization of the machine of the 115 Tripp patent previously identified, it should be understood that the invention is equally applicable to heel building machines of other specific forms of construction, and it is contemplated that it shall be so used.

Having described my invention, what is claimed as new and desired to be secured by Letters Patent of the United States is:

1. In a heel building machine, the combination of a contractile heel form, mechanism 125 for applying pressure to the heel in a direction normal to the planes of the lifts, automatic means for contracting the form upon the lateral surface of the heel to aline the lifts, and interdependent nailing mechanism 130

and means for uninterruptedly maintaining the form in expanded condition until the operation of the pressure applying mechanism is started.

5. 2. In a heel building machine, the combination of a contractile heel form, mechanism for applying pressure to the heel in a direction normal to the planes of the lifts, automatic means for contracting the form 10 upon the lateral surface of the heel to aline the lifts, and interdependent nailing mechanism and positive means for uninterruptedly maintaining the form in expanded condition until the operation of the pressure 15 applying mechanism is started.

3. In a heel building machine, the combination of a contractile heel form, mechanism for applying pressure to the heel in a direction normal to the planes of the lifts, 20 yielding means for contracting the form upon the lateral surface of the heel to aline the lifts, and interdependent nailing mechanism and means for uninterruptedly maintaining the form in expanded condition 25 until the operation of the pressure applying mechanism is started.

4. In a heel building machine, the combination of a contractile heel form, mechanism for applying pressure to the heel in 30 a direction normal to the planes of the lifts, yielding means for contracting the form upon the lateral surface of the heel to aline the lifts, and interdependent nailing mechanism and positive means for uninterruptedly 35 maintaining the form in expanded condition until the operation of the pressure applying mechanism is started.

5. In a heel building machine, the combination of a contractile heel form, mechanism 40 for applying pressure to the heel in a direction normal to the planes of the lifts, mechanism for nailing the lifts together, automatic spring means for contracting the form upon the lateral surface of the heel 45 to aline the lifts, and separate means for maintaining the form expanded except when the pressure mechanism is operated.

6. In a heel building machine, the combination of a contractile heel form, mechanism 50 for applying pressure to the heel in a direction normal to the planes of the lifts, mechanism for nailing the lifts together, automatic means for contracting the form upon the lateral surface of the heel to aline 55 the lifts, and separate automatic means, always operative when the pressure mechanism is quiescent, to expand the form to permit the introduction of lifts.

7. In a heel building machine, the combination of a contractile heel form, power 60 nailing mechanism, yielding means for contracting the form upon the lateral surface of the heel to aline the lifts, and separate means, controlled by an element of said 65 power nailing mechanism, for keeping the

form expanded to permit the introduction of lifts when the nailing mechanism is inoperative.

8. In a heel building machine, the combination of a contractile heel form, power 70 mechanism for applying pressure to the heel, automatic means for contracting the form upon the lateral surface of the heel to aline the lifts, and separate cam means, stationary 75 when said power mechanism is not in operation, operated by an element of said power mechanism, for keeping the form expanded to permit the introduction of lifts.

9. In a heel building machine, the combination of a contractile heel form, power 80 mechanism for applying pressure to the heel, spring means tending to contract the form, and a cam, operated by said power mechanism, for keeping the form expanded against 85 the tension of the spring when said power mechanism is not in operation.

10. In a heel building machine, the combination of a heel form, mechanism for driving a nail through a heel in the form, a presser movable over and away from the 90 form, and means permitting the presser to be moved over the form but preventing its retraction until the nail has been driven.

11. In a heel building machine, the combination of a heel form, mechanism for driving a nail through a heel in the form, a presser movable into and out of alinement 95 with the nailing mechanism, and means for preventing movement of the presser out of alinement with the nailing mechanism prior 100 to the operation of said mechanism.

12. In a heel building machine, the combination of a heel form, mechanism for driving a nail through a heel in the form, a presser movable into and out of alinement 105 with the nailing mechanism, and means under the control of said mechanism constructed and arranged to permit the presser to be drawn forward into operative position in alinement with the nailing mechanism 110 and then to lock and retain it in that position until after the operation of said mechanism.

13. In a heel building machine, the combination of a heel form, mechanism for driving a nail through a heel in the form, a presser movable into and out of alinement 115 with the nailing mechanism, and a latch under the control of said mechanism constructed and arranged to permit the presser to be drawn forward into operative position in alinement with the nailing mechanism 120 and then to lock and retain it in that position until after the operation of said mechanism.

14. In a heel building machine, the combination of a heel form, a presser movable laterally relatively to the form and vertically relatively to a heel in the form, and means for insuring that the lateral and ver- 130

tical movements of the presser shall succeed each other alternately.

15. In a heel building machine, the combination of means for supporting a heel blank, and a presser laterally movable over and away from the blank in a path sufficiently close to the face of the blank to insure against the presence of an operative's fingers between the presser and the blank.
- 10 16. In a heel building machine, the combination of means for supporting a heel blank, a presser laterally movable over and away from the blank, said presser being so constructed and arranged that in its movement into operative position over the blank it will engage and push away the fingers of an operative in case they have not been previously removed, and means for actuating the presser to apply pressure to the blank.
- 20 17. In a heel building machine, the combination of a heel form, a presser carrying member movable into and out of alinement with the blank in the form, and a blank engaging presser mounted upon said member for movement over the blank in a path sufficiently close to the blank to insure against the presence of an operative's fingers between the presser and the blank.
- 25

18. In a heel building machine, the combination of a heel form, a presser carrying member movable into and out of alinement with the form, and a heel engaging presser mounted for positively limited yielding movement upon said member during the pressure applying operation.

35 19. A heel building machine comprising an upwardly facing lift receptacle, a platen adapted to coöperate with said receptacle and including a power actuated inner head, and a loose outer head normally separated from the inner head when the platen is moving toward the receptacle, said outer head constituting a safety device.

20. A heel building machine comprising an upwardly facing lift receptacle, a platen 45 adapted to coöperate with said receptacle and including a power actuated inner head, and a loose outer head normally separated from the inner head when the platen is moving toward the receptacle, said outer head 50 constituting a safety device and being provided with a face arranged to press upon a lift in the receptacle.

In testimony whereof I have signed my name to this specification.

JOSEPH H. POPE.
